(57) **CLAIM**

The ornamental design for an aquarium filter cartridge with
tab, as shown and described.

DESCRIPTION

FIG. 1 is a front elevation view of a first embodiment of an
aquarium filter cartridge with tab showing a new aquarium
filter cartridge profile design; the portions of the aquarium
filter cartridge with tab shown in broken lines forming no part
of the claimed design.

FIG. 2 is a side perspective view of the first embodiment of the
aquarium filter cartridge with tab of FIG. 1.

FIG. 3 is a front elevation view of a second embodiment of an
aquarium filter cartridge with tab showing a new aquarium
filter cartridge profile design; the portions of the aquarium
filter cartridge with tab shown in broken lines forming no part
of the claimed design; and,

FIG. 4 is a side perspective view of the second embodiment of
the aquarium filter cartridge with tab of FIG. 3.
